1 Claim

ABSTRACT OF THE DISCLOSURE

An electric timepiece having an oscillating regulator wherein electric and electromagnetic means maintain the oscillations of the regulator. These means comprise at least two magnets and two coils, through which coils an electric current momentarily flows. The relative movement of at least one of the coils, with respect to the magnets, is adapted to produce pulses which keep the regulator going.

The coils form part of an electronic circuit having a transistor and at least one resistance and one condenser.

BACKGROUND OF THE INVENTION

Field of the invention

During the normal running of the regulator, the resistance and condenser introduce into the circuit a time constant of a value such that the condenser charge maintains the blocking polarization of the transistor at a value which is variable yet sufficient to prevent it from becoming conductive under the action of secondary electrical pulses of the same sign but dephased with respect to the electrical maintaining pulses, the latter pulses along can unblock the transistor when the condenser is charged or partially discharged, on the other hand, when the time piece is energized, the charging current of the condenser produces the starting pulse for the regulator. Before the condenser is charged, the secondary pulses render the transistor conductive and thereby assist momentarily in initial acceleration of the regulator.

Description of the prior art

In the prior art circuits, nothing is provided for cancelling each second pulse, wherefore all pulses are used for driving the mechanical oscillator, such being undesirable, chronometrically speaking.

SUMMARY OF THE INVENTION

The invention is a self-starting circuit which uses only one half of the pulses by removing each second pulse. During a starting period, all positive pulses are used for oscillator driving so as to allow a self-starting feature, but during the running frequency period all the secondary pulses are eliminated.

In the prior art circuits, nothing is provided for cancelling each second pulse. Thus, all pulses are used for driving the mechanical oscillator. It is not desirable, from a chronometrical view point to drive an oscillator for instance a balance wheel twice at each complete oscillation so that it is useful as the present arrangement teaches, to eliminate each second pulse whereby only one pulse is applied to the oscillator at each oscillation thereof.

An elimination of each second pulse is desirable but at the same time the device must be self-starting.

Condenser 17 of the invention is not directly connected to emitter 9 of transistor T, but is connected to the emitter through the source of current.

In the circuit according of the invention, the base of transistor T is substantially at the same tension as the collector. In this condition, the transistor is very conduc-

2

tive and a strong current circulates in the output circuit, giving a strong driving pulse to the balance wheel. Owing to the characteristics of the transistor, to the output current in the circuit, corresponds an input current in the circuit which has for consequence to load rapidly the condenser 17, as it would be the case if a weak resistance was put in parallel with the resistance 18. Thus, the constant of time is momentarily reduced to a value of 0.1 second, for instance. Transistor T is thus rapidly in a condition where it can use the initial deviation of the balance wheel and apply to it maintaining pulses.

The resistance and condenser are connected to the base of the transistor for introduction into the circuit (during normal regulator running by the resistance and condenser) of a time constant of a value for the maintaining by the charge of the condenser of a blocking polarization of the transistor at a value sufficient to prevent it from becoming conductive under the action of secondary electrical pulses of the same sign but dephased with respect to the electrical maintaining pulses capable of unblocking the transistor as the condenser is partially discharged.

BRIEF DESCRIPTION OF THE DRAWINGS

FIG. 1 is an elevational view of a part of a regulating device for the electric timepiece;

FIG. 2 is a cross-section on the line II—II of FIG. 1; FIGS. 3, 4 and 5 show in diagrammatic form various stages of the relative movement of a movable part of the regulating device with respect to its fixed part;

FIG. 6 shows a diagram of pulses, as a function of time;

FIG. 7 is a diagram of an electrical maintaining circuit for the regulating device shown in FIGS. 1 and 2; and

FIG. 8 is a diagram of the variations in voltage as a function of time between two points of the circuit shown in FIG. 7.

DESCRIPTION OF THE PREFERRED EMBODIMENT

The regulating device, or balance, features opposed magnets 1, 1' and 2, 2', secured in pairs on plates 4 mounted rotatively on the frame of the clockwork by means of staff 5.

The balance is subject to the action of a spiral return spring (not shown).

Two coaxial coils 6 and 7, fixed with respect to the balance and having their axes parallel to the axis of staff 5, are disposed so that their turns can intersect the parallel groups of the lines of force of magnets 1, 1' and 2, 2'. These groups are movable around the axis of staff 5, according to the amplitude and the period of the balance.

Pole pieces 3 and 3' each join the two poles of opposite polarity of magnets 1 and 2, on the one hand, and of magnets 1' and 2' on the other hand, so that the balance carries a magnetic field including two gaps 1-1' and 2-2' which sweep respectively and in succession over the turns of coils 6 and 7.

It is to be noted that, instead of coils 6 and 7 being superposed, as shown, they could be arranged one inside the other or could be overlapped one within the other by simultaneous winding.

As the balance passes through its position of equilibrium, magnets 1, 1' and 2, 2' are disposed symmetrically with respect to coils 6 and 7 as in FIG. 2. Pairs of magnets 1, 1' and 2, 2' are fixed in the vicinity of the rims of plates 4 so as to sweep over the turns of the coils at maximum linear speed.

The variations in flux, and the induced voltages which result therefrom within coils 6 and 7, can be split up into three essential stages corresponding to the different rela-

tive positions of the magnetic field of magnets 1, 1' and 2, 2' with respect to coils 6 and 7 (FIGURES 3, 4 and 5).

In FIG. 3, group 2-2' of the field is shown as beginning to sweep over a part of the coils so as to coincide, as shown in FIG. 4, with the position of equilibrium of the balance, the turns of coils 6 and 7 intersecting the maximum lines of force of the magnetic field.

In FIG. 5, the field is shown as tending to move away from the coils, only group 1-1' still acting on a part of the latter.

These different stages of movement give rise, in the circuit of coils 6 and 7, to the voltage pulses indicated in FIG. 6.

Successive trains of three pulses appear at each half-period. A main pulse C or C' is framed by two secondary pulses B, A or A', B' with a sign always opposite to that of the main pulses of the same train. The secondary pulses of type A, A' correspond to the stage of FIG. 3, while the secondary pulses of type B, B' correspond to the stage of FIG. 5.

The main pulses of type C, C', which are positive or negative according to the direction of the half-oscillation of the balance and of an amplitude greater than that of the secondary pulses, correspond to passage to the position of equilibrium (FIG. 4), simultaneously by the turns of coils 6 and 7.

During the process of maintaining the movement of the regulator by electromagnetic pulses, only the positive pulses, due to the fact that the circuit of FIG. 7 is transistorized, are adapted to unblock transistor T and render it conductive. The negative pulses (in chain-dotted lines in FIG. 6) do not give rise to any maintaining energy.

From among the positive pulses shown in FIG. 6, we select only those necessary (i.e., the main ones), for the maintenance of the regulator movement.

The electrical circuit (FIG. 7) comprises a battery of which negative pole 8 is connected to emitter 9 of a transistor T of the n-p-n type. Collector 10 is connected to end 11 of coil 6. The other end 12 of coil 6 is connected to positive pole 13 of the battery.

Base 14 of transistor T also terminates at 13 through the medium of coil 7, having ends 15 and 16 in series with condenser 17 having a capacity C.

The circuit also includes a resistance 18 with an ohmic value R and connected between positive terminal 13 and end 15 of coil 7 so as to be in parallel with the assembly consisting of coil 7 and condenser 17.

A second condenser 19, with a capacity C', is interposed between collector 10 and base 14 of transistor T, which condenser 19 serves to suppress oscillation in the circuit which would occur at its own frequency, by reason of the fact that since coils 6 and 7 are arranged one against the other, they have a certain coefficient of mutual induction. Condenser 19 dephases the voltages of the coils at this high frequency sufficiently, but has no effect on the very low frequency pulses, which are alone used.

When the FIG. 7 circuit is under no voltage, the balance is stopped in the position of equilibrium, as shown in FIGS. 1 and 2, magnets 1, 1' and 2, 2' being disposed symmetrically with respect to coils 6 and 7.

At the moment of connecting the circuit to the source, condenser 17 being discharged (the voltage at its terminal is equal to zero), interconnected points 14, 15 and 16 are subjected instantaneously to the potential of positive pole 13.

This polarization voltage has the effect of rendering the transistor conductive. A current is set up from positive pole 13, through coil 6 and towards collector 10 and emitter 9, to terminate at negative pole 8 of the battery that produces a starting punch applied to the oscillator. At the same time, the current in the circuit of base 14 charges condenser 17 through coil 7. This has the effect of reducing the positive polarization of base 14 and of causing the collector current to fall very rapidly. The collector current establishes itself at a very low value,

when the charge of condenser 17 brings the potential of base 14 to a value close to the conduction threshold of transistor T.

The initial pulse, on the placing of the circuit under voltage, has the effect, in passing through both coils 6 and 7, of inducing a magnetic field which, coupled with the field of magnets 1, 1' and 2, 2', produces an important force displacing the balance. (It is to be pointed out that the main effect is due to coil 6, rather than the coil 7.)

In turn, the displacement of the balance, and the associated magnetic field, induces in coil 7 a voltage of low value sufficient to initiate momentarily conduction of the transistor, which is therefore polarized in the vicinity of its conduction threshold. This induced voltage is therefore amplified and supplies pulses A', B' and C to coil 6.

This cycle causes self-starting and acceleration of the balance until it has reached its normal running amplitude.

Moreover, and this is one of the essential aims of the invention, the circuit described has the effect of also rendering inoperative, during the normal operation of the regulating device, the secondary positive pulses of type A', B' (FIG. 6) which are induced at each half-period following or preceding the main positive maintaining pulse. This special property of the circuit of FIG. 7 can be explained as follows:

Under normal working conditions, at each pulse crossing collector 10, the base current of the transistor charges condenser 17 to a voltage which, measured at its terminals, is close to the supply voltage of the circuit. Condenser 17 is discharged, between the two successive pulses, through resistance 18 and in accordance with the exponential law which determines the time constant $\tau = CR$. The values of R and C are chosen in such manner that the time constant τ is large with respect to the period of the pulses to be amplified. The result is that the residual voltage at the terminals of condenser 17 is sufficient in comparison with the voltage of the secondary pulses A', B' for the polarization voltage not to permit the unblocking of the transistor.

The conduction threshold of the transistor not being reached, for pulses of low amplitude, as is the case with the secondary pulses A' and B', the latter (in broken lines in FIG. 6) are not amplified.

After a time of about a half-period following the appearance of pulse B', which pulse has had no effect on the amplifying power of transistor T, pulse C arrives (pulse C being indicated in solid lines in FIG. 6). The latter pulse renders the transistor conductive owing to the facts that it is higher than pulses A' and B' and that condenser 17 has continued to discharge itself during this half-period, so that, at the instant in question, its residual charge no longer has an inhibiting action on the voltage of main pulse C (FIG. 6), which voltage alone initiates the conduction of transistor T, thus giving rise to maintaining pulse through coil 6, at the same time as condenser 17 is charged afresh.

In other words, the presence of condenser 17 and its special time constant prevent any secondary pulse, dephased with respect to the main pulses, from priming the transistor, so that these secondary pulses, even were they of the same sign as the main pulse, are rendered inoperative.

This is evident from FIG. 8, which indicates, as a function of time, the form of the variable voltage U existing between emitter 9 and base 14 of transistor T. The zero of the ordinates corresponds to that of the emitter potential. The successive voltage peaks a', c', b', d, c, a are produced at the same time as the pulses A', C', B', B, C, A shown in FIG. 6. The chain-dotted positive ordinate horizontal shows the conduction threshold of the transistor T, which threshold is reached only by the voltage U_c (peak c in FIG. 8) corresponding to the main pulse C (FIG. 6). Moreover, the voltages resulting from the charging and discharging of condenser 17 are clearly ap-

parent between the successive oscillation trains of the voltages.

The capacity of condenser 17 is essentially a function of the amplification coefficient β of transistor T, but for the balances generally used and with the transistor employed, the capacity of condenser 17 is preferably between 0.4 μ f. (β large) and 1.5 μ f. (β small). Resistance 18 may have an ohmic value ranging between 2.5 and 4 mohms, so that it is possible to accept for the time constant τ which has been mentioned, values corresponding to 1 to 6 seconds (1 sec. $\leq \tau \leq 6$ sec.). Moreover, if t is the period of the oscillator, experience shows that τ minimum must be at least equal to $3.5t$ for the polarization not to vary too rapidly from one pulse to the next following.

Eliminating any maintaining pulse which is dephased with respect to the passage of the balance to its position of equilibrium is favorable to attaining maximum efficiency of the whole device. The maintaining pulses are produced at the moment when the magnetic field intersecting the turns of the coils is at the maximum (FIG. 4). Since the transistor remains blocked during the secondary pulses and between the various pulses, the supply current is reduced to the leakage current of the transistor, which is very low by itself.

This features is favorable to the isochronism of the movement and enables the latter to be regulated by displacement of the pulse relative to the position of equilibrium of the balance and by means of only one driving pulse per complete oscillation of the oscillator.

Although the secondary pulses are inoperative during the normal working conditions of the regulator, the position is not the same at the moment of starting when, since condenser 17 is not yet fully charged, the first positive secondary pulses A', B' can momentarily render transistor T conductive and consequently assist, for a brief moment, in setting the balance going by a supplementary, but temporary, supply of energy.

With the timepiece being energized, the charging current of the condenser produces a starting pulse for the regulator. Then, preliminary to the charge of the condenser, secondary pulses render the transistor conductive for momentarily assisting in the initial acceleration of the regulator.

The combination allows the following operations: (1) Strong self starting of the oscillator due to the fact that the current, at the moment of energizing the circuit, passes freely through the condenser 17 which is unloaded so that both coils 6 and 7 receive current and both act on the oscillator for imparting to it a strong impulse like a "big punch";

(2) Very rapid acceleration of the oscillator up to the running amplitude due to the fact that, during this starting period, all the positive pulses (main pulses as well as secondary pulses) are used. (The condenser 17 is not sufficiently loaded for having an inhibiting action); and

(3) Very favorable running condition from the point of view of the isochronism since, once the running conditions

are reached, the secondary pulses are no longer used (the condenser 17 being loaded), so that only the main pulses are used, i.e., only one pulse for each complete oscillation of the oscillator is applied thereto.

I claim:

1. In a self-starting oscillating regulator of an electric timepiece comprising:

a shaft having two rim plates rotatably mounted thereon and electromagnetic means for maintaining the oscillations of the regulator and including:

(A) a pair of magnets carried by each of said plates and each pair of magnets being positioned directly opposite the other pair of magnets, and
(B) an electronic self-starting circuit with each second pulse removed and constituted by:

(1) a current source,
(2) a transistor,
(3) a resistance connected to the transistor base through the current source,
(4) a condenser connected to the transistor base through the current source with the resistance and condenser being mounted in parallel, and

(5) a pair of stationary coils generating regulator-driving pulses upon movements relative to the magnets with a relative movement between the magnets and coils occurring during oscillations of the regulator and with normal regulator operation being characterized by a time constant having a value for maintainance by the condenser charge of a blocking polarization of the transistor at a variable value for preventing conduction by the transistor under the action of secondary electrical pulses of the same sign but dephased with respect to the maintaining pulses, the maintaining pulses being such as to unblock the transistor as the condenser is charged or partially discharged and the secondary pulses rendering the transistor conductive for momentarily assisting initial regulator acceleration.
